UNITED STATES PATENT OFFICE.

WILLIAM W. STRAWN, OF TULSA, OKLAHOMA.

FLEXIBLE-METAL WEATHER STRIP.

Application filed January 22, 1927. Serial No. 162,832.

My present invention has to do with weatherstripping and more particularly the weather stripping of sliding sashes which are liable to swell and shrink; and it has for its object the provision of a flexible metal weather strip which while it is simple and inexpensive in construction and is susceptible of ready installation, is adapted to accommodate itself to all conditions of the sash so as to insure a free acting sash and at the same time exclude the weather.

To the attainment of the foregoing the invention consists in the improvement as hereinafter described and definitely claimed.

15 In the accompanying drawings, forming part of this specification:

Figure 1 is a face view of a portion of a flexible metal weather strip constructed in accordance with my invention.

20 Figure 2 is a horizontal section showing the interposition of my novel weather strip between one vertical edge of the sash and the side stile of the sash frame.

Figure 3 is an end elevation of the weather strip per se.

Figure 4 is a similar view of a modified weather strip.

Similar numerals of reference designate corresponding parts in Figures 1 to 3, to 30 which reference will be first made.

I show in Figure 2 a side stile 1 of a sash frame in which is a channel 2 alongside a parting strip 3; the stile being also provided with a stop 4 spaced from the parting strip 3 as shown to provide for the reception between the parting strip 3 and the stop 4 of the edge portion of a sliding sash 5. In the edge portion of the sliding sash 5 is a groove 6.

40 My novel flexible metal weather strip per se is designated by 7 and it will be understood as having a bead 8, a tongue 9 with a lapped portion 10, and a rib 11. The beforementioned groove in the sash 5 is preferably U-shaped in cross section, and the rib 11 is of V-shape in cross section. This assures maximum flexibility of the strip and insures a free acting sash and close contact between the strip and sash under all conditions. The tongue 9 is designed to be ar-

45 ranged alongside the parting strip 3 and in the channel 2 as appears in Figure 2 and is adapted to shift its position in the channel 2 as the sash 5 swells or shrinks. The strip 55 is also provided with an edge portion 12 adapted to be interposed between the stop 4

and the stile 1. The bead 8 is adapted when flexed by the stop or by nails to raise the rib 11 so as to properly contact with a very loose sash. While I prefer to employ the 60 said edge portion 12 on the strip, I would have it understood that the said edge portion 12 is not essential to the practice of my invention, and therefore said edge portion 12 may in some cases be altogether omitted 65 from the strip as is the case in the embodiment of the invention shown in Figure 3.

It will be apparent from the foregoing that my improvement as thus far described is simple and inexpensive, the strip being 70 susceptible of ready production, and being adapted to be installed, and being calculated when properly installed to prevent the passage of weather between the sash and the stile of the sash frame under all conditions.

75 The modified strip 7x shown in Figure 4 is manifestly less expensive than the embodiments shown in Figures 1, 2 and 3. It will be noted that the strip 7x lacks the tongue 9; the end of the said strip 7x being adapted 80 to be opposed to and wipe against the adjacent side of the parting strip 3.

While I prefer to employ the embodiments illustrated and specifically described in the manner hereinbefore set forth, I do not desire to be understood as limiting myself to the precise construction and arrangement of the weather strip as disclosed, my invention being defined by my appended claims within the scope of which modifications may be 85 made without departure from my invention.

Having thus described the invention, what I claim is:—

1. In combination, a sash having a groove 95 in its edge, a sash frame having a stop and parting strip spaced from the stop, and a flexible metal weather strip interposed between the stop and the parting strip and movable between the edge of the sash and the sash frame and having at an intermediate 100 point in its width a rib extending laterally from the major portion of the strip and disposed in the groove of the sash; the said groove being of U-shape in cross section, and the said rib of the strip being of V-shape 105 in cross section.

2. In combination, a sash frame having in its edge a groove of U-shape in cross section, a sash frame having a stop and a parting strip spaced from the stop and also having 110 alongside the parting strip a channel, and a flexible metal weather strip interposed be-

tween the stop and the parting strip and movable between the sash and the sash frame and having an edge portion interposed between the stop and the sash frame and a bead adjacent to the stop and further having at an intermediate point in its width a lateral V-shaped rib disposed in the groove of the sash and further having at its opposite edge an angularly disposed tongue movable alongside the parting strip and in the said ¹⁰ channel of the sash frame.

In testimony whereof I affix my signature.

WILLIAM W. STRAWN.
